CLAIM

I claim the ornamental design for the vacuum bottle, as shown and described.

DESCRIPTION

FIG. 1 is a perspective view of a vacuum bottle showing my new design;

FIG. 2 is a front elevational view thereof, the opposite side being a mirror image thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a cross-sectional view thereof taken along line 7—7 of FIG. 3;

FIG. 8 is a perspective view with spout cap removed and stopper closed thereof; and,

FIG. 9 is a perspective view with spout cap removed and stopper opened thereof.
